Patented July 20, 1976

240,660

COMBINED PHONOGRAPH AND CARTRIDGE PLAYER

Leonard Kaye, Westfield, N.J., assignor to Capehart
Corporation, New York, N.Y.

Filed Nov. 25, 1974, Ser. No. 526,522

Term of patent 14 years

Int. Cl. D14—01

U.S. Cl. D56—4 R

FIG. 1

FIG. 2

FIG. 4

FIG. 5

FIG. 3

FIG. 6

FIG. 1 is a front, top and right side perspective view of a combined phonograph and cartridge player showing my new design;

FIG. 2 is a front elevational view;

FIG. 3 is a left side elevational view;

FIG. 4 is a right side elevational view;

FIG. 5 is a top plan view; and

FIG. 6 is a bottom plan view.

The rear of the base of the combined phonograph and cartridge player is plain and unornamented.

I claim:

The ornamental design for a combined phonograph and cartridge player, as shown and described.
